United States Patent Office

Des. 189,770
Patented Feb. 14, 1961

189,770

NOISELESS ELECTRIC TYPEWRITER

Carl W. Sundberg, Bloomfield Hills, and Montgomery Ferar, Huntington Woods, Mich., and David B. Converse, Wilton, Conn., assignors to Sperry Rand Corporation, New York, N.Y., a corporation of Delaware

Filed Sept. 2, 1959, Ser. No. 57,409

Term of patent 14 years

(Cl. D64—11)

FIG. 1

FIG. 2

Fig. 1 is a front perspective view of a noiseless electric typewriter showing our new design; and Fig. 2 is a rear perspective thereof.

We claim:

The ornamental design for a noiseless electric typewriter, as shown.
